ANTI-FOULANT FOR HYDROCARBON FEED STREAMS

Richard J. Lee, Park Forest, Ill., assignor to Standard Oil Company, Chicago, Ill., a corporation of Indiana
No Drawing. Filed Apr. 19, 1966, Ser. No. 543,510
10 Claims. (Cl. 208—48)

ABSTRACT OF THE DISCLOSURE

A method for inhibiting the deposition of fouling materials on equipment surfaces caused by liquid hydrocarbons passing through the equipment at elevated temperatures, which method includes incorporating into the liquid hydrocarbons a small amount of an alkenylsuccinimide derivative of polyamino urea. An anti-foulant material of this invention is conveniently formed by first reacting a polyalkylene amine (polyamine) with urea to form polyamino urea and then reacting the resulting polyamino urea with a mono-alkenyl substituted succinic anhydride.

This invention relates to the treatment of refinery feed stream hydrocarbons and more particularly pertains to the treatment of hydrocarbon feed streams which have a tendency to form equipment-fouling deposits when heated to a temperature above about 300° F. before subjecting the feed streams to refinery processes including separation processes, upgrading processes and hydrocarbon conversion processes. More specifically, the invention relates to a method for inhibiting, to a substantial extent, the propensity of said hydrocarbon feed streams to form fouling materials such as gums, sediment and similar deposit formers during and after preheating.

In many refinery processes hydrocarbon streams both unrefined and partially refined hydrocarbons are preheated before being subjected to liquid and/or vapor phase processing. For example, crude petroleum is preheated by indirect heat exchange with product stream and then subjected to final preheating in a furnace before charging to a pipe still for the separation and recovery of various petroleum fractions. Likewise, topped crude is preheated before being subjected to vacuum distillation for the separation and recovery of hydrocarbon fractions of said topped crude. Other unrefined liquid hydrocarbon streams such as natural gas liquids are also preheated before being subjected to refinery processes. Partially refined liquid hydrocarbons such as virgin gas oil, gas oil from vis-breaking, gas oil from coking, light gas oil, virgin naphtha, light and heavy naphtha fractions from pipe still distillation, paraffin distillates, cycle oil from catalytic cracking, coker naphtha, and other such partially refined liquid hydrocarbons are preheated before being subjected to such hydrocarbon conversion processes as thermal cracking, catalytic cracking, thermal reforming, catalytic reforming and other conversion processes. In addition, preheating is employed before liquid hydrocarbon feed streams are subjected to hydrocarbon enrichment or upgrading processes as absorption enrichment of lean oil and/or stripping processes. For these hydrocarbon separation processes, hydrocarbon enrichment processes and hydrocarbon conversion processes, the unrefined and partially refined liquid hydrocarbon feeds are preheated to temperatures over a wide range depending on the temperature requirements of further processing and depending upon the physical phase involved in the further processing such as liquid phase, vapor phase or a combination of liquid and vapor phases. In general, the various preheating temperatures are within the range of 300 to 1500° F.

It is recognized in petroleum refining that the various

2

refinery feed streams would present fewer problems with respect to fouling of heating surfaces and fouling of process stream filters, generally in-line filters, provided that these feed streams had not been contacted with oxygen, especially air. Contact with air might be avoided when petroleum fractions and process hydrocarbon fractions are immediately charged to further separation upgrading and/or conversion processes. To do so would require all refinery operations to be conducted on a totally continuous basis. Such total continuous refining is not feasible and various liquid hydrocarbon streams must be held in storage before they are further used in other refinery processes. Even continuous refinery operation would not prevent air contact with crude petroleum or other crude hydrocarbons such as natural gas liquids, for these crude hydrocarbons cannot be produced and transported to refineries without contact with air. Since these air contacted sources of crude hydrocarbons do have the tendency to form gums and/or sediments upon preheating for use in refinery processes and use even in a totally continuous refinery operation, would still present the problems of fouling heating surfaces and in-line filters.

Blanketing of unrefined and partially refined liquid hydrocarbons with inert gas such as nitrogen has been proposed to partially alleviate the problems encountered by fouling of heating surfaces of heat exchangers during preheating steps and the after-fouling by preheated liquid hydrocarbons of filtering devices installed to prevent undesirable suspended gums, sediments, etc. from entering refinery processes. Certain chemical compounds and mixtures of chemical compounds have been proposed as additives for the unrefined and partially refined liquid hydrocarbons as anti-foulant additives to reduce the tendency for gum and/or sediment formation during preheating in heat exchangers beyond that fouling reduction achieved by inert gas blanketing of stored liquid hydrocarbons. Most of the commercially available anti-foulants are propriety compositions sold under various trade names, trademarks and grade marks. Consequently, their precise chemical composition cannot be readily ascertained.

A class of new anti-foulants has been discovered which can be used in small amounts as additives for unrefined and partially refined liquid hydrocarbons which have a propensity for depositing fouling materials such as gums and/or sediments upon being heated to a temperature above 300° F., in the range of 300 to 1500° F., which anti-foulant additives inhibit and prevent, to a substantial extent, the fouling of heat exchange surfaces, piping, valves, process stream filters etc., by the gum and/or sediments which would normally be formed. The class of anti-foulants for use in the method of this invention in said unrefined and partially refined liquid hydrocarbons to be preheated are reaction products obtained by reacting a "polyalkylene amine" with urea employing these reactants in the ratio of about two moles of polyalkylene amine for each mole of urea to form a polyamino urea which is then reacted with alkenylsuccinic anhydride as described hereinafter. By "polyalkylene amine" is meant those polyamines having the formula

wherein x is an integer of from 2 to about 10, R is hydrogen or a lower alkyl hydrocarbon substituent and "alkylene" is a lower alkylene, i.e. divalent, open chain, hydrocarbon group having from 1 to 8 carbon atoms. Individual polyalkylene amine compounds may be used or mixtures of various such polyalkylene amines may be employed. Such polyalkylene amines include methylene amine, ethylene amines, propylene amines, butylene amines, pentylene amines, hexylene amines, heptylene amines, octylene amines, and other polymethylene amines

which contain from 2 to 10 alkylene groups and 3 to 11 nitrogens.

Specific examples of such polyalkylene amines include diethylene triamine, triethylene tetramine, tetraethylene pentamine, pentaethylene hexamine, heptaethylene octamine, dipropylene triamine, tripropylene tetramine, tetrapropylene pentamine, dibutylene triamine, tributylene tetramine, tetrabutylene pentamine, dimethylene triamine, trimethylene tetramine, tetramethylene pentamine, pentamethylene hexamine, di(heptamethylene) triamine, di(trimethylene) triamine, decaethylene heptadecamine, decamethylene heptadecamine, N_1, N_3 -dimethyl diethylene triamine, N_1, N_5 -dimethyl tetraethylene pentamine, N_1, N_5 -diethyl tetraethylene pentamine, dipentylene triamine, trihexylene tetramine, tetraheptylene pentamine, trioctylene tetramine, and tetrapentylene pentamine among others.

The foregoing polyalkylene amines where R is hydrogen are generally prepared by reacting an alkylene dihalide such as methylene dichloride, ethylene dichloride, propylene dichlorides, butylene dichlorides, pentylene dichlorides, hexylene dichlorides, heptylene dichlorides and octylene dichlorides with ammonia. Where R is lower alkyl i.e. methyl, ethyl, propyl butyl, the alkylene dichloride-ammonia reaction product can be further reacted with the appropriate lower alkyl chloride.

The polyamino ureas of this invention are formed according to the following reaction equation where tetraethylene pentamine, illustrative of the polyalkylene amine reactant, and urea react in a 2:1 mole ratio.

The resulting polyamino urea has the ten amino groups and the eight ethylene groups. There are also present in the polyamino urea product other polyamino ureas similar to that illustrated wherein the carbamide groups are from secondary amino nitrogens other than those shown and polyamino urea such as illustrated by the following:

For the purpose of discussion of this invention the class of polyamino urea is defined as "reaction product of two moles of polyalkylene amine with one mole urea."

The polyamino urea reaction product of two moles polyalkylamine with one mole urea is prepared by conducting the reaction with or without a reaction diluent, preferably without, at a temperature in the range of 200 to 500° F. As hereinbefore indicated the reaction is complex not only because of the different types of polyamino urea products which form at one time but also because of additional side reactions, for example polymerization of monosubstituted urea and biuret formation. The complexity of the condensation reaction between two moles of polyalkylene amine with one urea can be illustrated by the following data in Table I obtained from the reaction of two moles tetraethylene pentamine with one mole urea at the designated temperatures for two hours.

TABLE I

Example No.	Reaction Temperature	Reaction Product Properties			
		Percent N-Total	Percent N-Basic	Basic N/Total N ¹	SSU Viscosity at 210° F.
1	250	31.78	22.7	72	93
2	300	31.43	20.4	67	85
3	350	29.83	18.0	61	96
4	400	29.61	17.8	59	166

¹ Ratio Percent N-Basic/Percent N-Total X 100.

The polyamino urea products of Examples 1 through 4 are subjected to infra red studies to determine relative densities of characteristic polyamino urea absorptions as determined from a ratio of absorbance at certain infra red frequencies to absorption at 1450 cm^{-1} .

These ratios are shown in Table II.

TABLE II.—RELATIVE DENSITIES OF CHARACTERISTIC POLYAMINO UREA ABSORPTION

Product of Example No.	IR Frequencies (cm^{-1})					
	1,695	1,607	1,560	1,492	1,330	1,270
1	1.51	0.903	0.872	0.584	0.616	0.677
2	1.53	0.598	0.588	0.885	0.441	1.00
3	2.00	0.454	0.262	0.929	0.349	1.13
4	2.04	0.519	0.265	0.966	0.343	1.20

25 11,667.

The increasing absorbance of frequencies 1695, 1492, and 1270 cm^{-1} are due to uramine concentration buildup as the reaction temperature is increased. Similarly, the decreasing absorbance of frequencies 1607, 1560 and 1330 cm^{-1} are due to the disappearance of reactants. Only two of the six frequencies are not known: 1492 cm^{-1} and 1330 cm^{-1} . The assignment of 1695 cm^{-1} and 1270 cm^{-1} as secondary amide bonds ($>C=O$ of Amide I and Amide III bonds respectively) and that of 1607 cm^{-1} and 1560 cm^{-1} as primary amide bonds (NH_2 of Amide II) are conventional.

Viscosity might be used to determine the extent of completion of the condensation reaction producing the polyamino urea. However, as indicated in Table III, viscosity of reaction product does not depend on length of time of reaction. The four reactions (Examples 5, 6, 7 and 8) all used two moles tetraethylene pentamine and one mole urea and the reactions were carried out at 300° F. for the length of time indicated.

TABLE III.—POLYAMINO UREA VISCOSITY VERSUS REACTION TIME

Example No.	Reaction Time, Hours	SSU Viscosity at 210° F.	
		Size	SSU
5	4		84
6	3		66
7	2		85
8	1		79.5

However, more constant viscosity values (SSU at 210° F.) are obtained when the reactants are combined at an elevated temperature. This is shown in Table IV for Examples 9, 10, 11 and 12 wherein the reactants are combined at two different temperatures: 180° F. and 300° F. and then reacted at 400° F. In these examples the size of the reaction mixture is indicated as "one mole batch" and "five mole batch" which mean that 2 moles of tetraethylene pentamine and one mole of urea are reacted in a "one mole batch" and ten moles of tetraethylene pentamine and five moles of urea are reacted in a "five mole batch."

TABLE IV.—EFFECT OF CHARGE TEMPERATURE

Example No.	Charge		SSU Viscosity at 210° F.
	Temperature (° F.)	Size	
9	180	One mole batch	76
10	180	Five mole batch	77
11	300	One mole batch	81
12	300	Five mole batch	80

75 Thorough mixing of urea with the polyalkylene amine to prevent agglomeration of urea and gradual heating of

the mixture from 180 to 220° F. to reaction temperature, preferably in the range of 375 to 425° F., produces poly-amino ureas of higher viscosity and higher nitrogen content. This is illustrated by the data in Table V from Examples 13, 14, 15, 16, and 17 wherein tetraethylene pentamine (TEPA) and urea are the reactants in a 2:1 mole ratio, the reactants are combined at 180° F. in all but Example 17 where the reactants are combined at ambient temperature (about 75-78° F.), different orders of combining the reactants, different degrees of mixing the combined reactants and different periods of heating up to reaction temperature of 400° F. were employed.

tion of solid or semi-solid sediment, and/or gums in process equipment.

The following example illustrates the preparation of the alkenyl succinic anhydride derivative of the poly-amino urea for use in the method of this invention.

Example 18

To a 3000-gallon kettle vented through a stack to the atmosphere there is charged 1254 gallons (9600 pounds) of a solution of polybutenyl substituted succinic anhydride having a molecular weight of about 960. This solution contains 54 weight percent of the substituted succinic

TABLE V.—MIXING EFFECT

Example No.	Order of Addition	Degree of Mixing	Time, hours		Product	
			Heat-up	Reaction	Percent N	SSU Viscosity at 210° F.
13	Urea to TEPA	Very vigorous	5	2	30	65.8
14	TEPA to urea	Vigorous	5	8	29	61.0
15	do	Stirring	1.25	6	27.6	58.0
16	do	Mild	5	8	28	56.0
17	Slurry TEPA and urea cold.	Very vigorous	5	5	32	105

It is preferred to first slurry the urea in a portion of the polyalkylene amine and add this slurry to the remainder of the polyalkylene amine heated to 180 to 220° F. with vigorous mixing and maintain vigorous mixing at least during heat-up to reaction temperature which heat-up period is preferably 3 to 5 hours.

Although in all of the foregoing seventeen illustrated examples tetraethylene pentamine and urea were the reactants employed, other specific polyalkylene amines of the types hereinbefore specifically named or mixtures thereof, can be used in the same reactions. Useful poly-amino ureas include those obtained from diethylene triamine, triethylene tetramine, trimethylene tetramine, tetramethylene pentamine, dipropylene triamine and tri-propylene tetramine.

The polyamino ureas, reaction product of two moles polyalkylene amine and one mole urea, is employed for the formation of succinimides through reaction with a mono-alkenyl substituted succinic anhydride having as its alkenyl substituent a hydrocarbon group derived from polyolefin of 30 or more carbon atoms especially poly-propylenes and polybutenes of 30 or more carbon atoms. The useful polypropylenes and polybutenes, and hence the alkenyl substituent, have a carbon content in the range of 30 to 200 carbons. The alkenyl substituent of the monoalkenyl succinic anhydride has a molecular weight in the range of from 400 to 100,000. The preparation of such monoalkenylsuccinic anhydrides by reacting maleic anhydride and a polypropylene or polybutene of said 400 to 100,000 molecular weight range is known.

The alkenylsuccinimide derivatives of the polyamino ureas are obtained by reacting, for each mole of mono-alkenyl substituted succinic anhydride, 0.4 to 0.7 mole of polyamino urea at 200 to 450° F., preferably 300 to 400° F., and aiding removal of by-product water by the use of an inert gas, e.g. nitrogen purge or by passing the inert gas through the reaction mixture. This reaction between monoalkenylsuccinic anhydride and polyamino urea is advantageously carried out in an inert diluent such as xylene or preferably a light hydrocarbon lubricating oil such as solvent extracted SAE 5W oil or white mineral oil or mixtures of these hydrocarbon oils with polybutene or polypropylenes of the 500 to 100,000 molecular weight range. It is desirable to conduct said succinimide reaction with proportions of reactants which will provide the succinimide product in concentrations of from 40 to 60 weight percent when a light hydrocarbon diluent is used. Such compositions are excellent concentrates for incorporating into unrefined and/or partially refined liquid hydrocarbon streams to inhibit the deposi-

30 anhydride dissolved in a mixture of 860 molecular weight polybutene and solvent extracted SAE 5W oil. Thus 5.4 moles of the polybutenyl succinic anhydride are charged. Also charged to the kettle are 339 gallons of additional solvent extracted SAE 5W oil. The resulting mixture is heated to 250-260° F. while blanketed with an inert gas such as nitrogen. Thereafter 122 gallons (1095 pounds or 2.7 pound moles) of a polyamino urea obtained by reacting two moles tetraethylene pentamine 35 with one of urea are pumped in over 60 minutes. This di(pentamino) urea has a nitrogen content of about 30.5, a total base number (MgKOH/gram) of about 815, a SSU viscosity at 210° F. of about 72, a gravity of about 9.0 and a 365° F. flash point. The reaction mixture is heated to 300° F. and held at this temperature for about 40 2 hours while sparging nitrogen through the reaction mixture to aid in the removal of by-product water, about 97 pounds. The resulting reaction mixture contains about 49 weight percent di(polybutenylsuccinimide) of the di(pentamino) urea. Filtration of the reaction mixture generally provides a brighter (clearer) product.

When tetraethylene pentamine is reacted with C₃₀ and higher alkenyl substituted succinic acids and/or anhydride lower temperatures of combining these reactants 45 are employed as well as lower initial reaction temperatures and slower rates of addition than are used in Example 18. The lower addition and reaction temperatures and slower addition rates are necessary to prevent excessive losses of tetraethylene pentamine.

Example 19

The process of Example 18 is repeated using 5.4 pound moles of polybutenyl succinic anhydride having a molecular weight of about 3100, 2.7 pound moles of the dipentamino urea and 11,825 pounds of SAE 5W oil as reaction diluent. The resulting filtered product was a clear, light colored solution containing about 60 percent by weight of the disuccinimide of the dipentamino urea.

Example 20

There are combined 2.7 pound moles of the dipentamino urea described in Example 18 and 5.4 moles of a polybutenyl succinic anhydride having a molecular weight of about 3100 as a 50 weight percent solution in about equal parts by weight of SAE 5W oil and 3000 molecular weight polybutene. After about 97 pounds of by-product water had been removed at 300° C. and sparging with inert gas, e.g., nitrogen, the reaction mixture is diluted further with SAE 5W oil, about 1000

pounds, to provide a 50 weight percent solution of the disuccinimide of the dipentamino urea.

The foregoing alkenylsuccinimide derivatives of polyamino ureas have been disclosed as being useful detergent additives for lubricating oils and detergent additives for internal combustion engine fuels. The discovery of the use of small amounts of these acylated nitrogen-containing derivatives as anti-foulants for unrefined and partially refined liquid hydrocarbons, which have the propensity upon heating at a temperature above 300° F. to form gum and/or sediment formations in the absence of the alkenylsuccinic anhydride-polyamino urea additive, is based on the unusual effect of these compounds in small amounts, i.e., from 1 to 100 parts per million of the liquid hydrocarbons. The observed unusual effect by the use of such small amounts of these compounds is achieved preferably by the use of such compounds derived from a substantially aliphatic hydrocarbon substituted succinic anhydride wherein the aliphatic hydrocarbon substituent has been derived from a polyisobutylene having an average molecular weight in the range of from about 560 to about 5000 and where the amine reactant is tetraethylene pentamine or a mixture of polyalkyl polyamines having a nitrogen content corresponding to tetraethylene pentamine. The latter mixture of polyethylene polyamines is an excellent low cost source of the polyamine reactant and when used herein in the specification claims, "tetraethylene pentamine" is intended to include both the tetraethylene pentamine per se and the commercially available polyethylene polyamine having a nitrogen content corresponding to the tetraethylene pentamine.

To illustrate the unusual effect of a small amount of anti-foulant according to this invention, the results of comparative screening tests with and without anti-foulant additive are employed. These screening tests were run in an Erdco Coker which is normally used for testing coking tendencies of distillate fuels. For these screening tests an Erdco Coker Model O2FC is used. This apparatus consists essentially of a continuous flow system with two heated sections (preheater tube and heated sintered metal test filter) which associated equipment for controlling and measuring temperature, pressure and flow rate. A detailed description of the apparatus is given in ASTM designation: D-1660-61T.

The experimental screen procedure is conducted by pre-filtering about 10 gallons of the liquid hydrocarbon to be used. The liquid hydrocarbon is then pumped con-

For the investigation of the hydrocarbon feed preheat exchanger fouling problem, a tube temperature of 400° F. and a filter temperature of 500° F. were used for all runs. This approximates typical preheat exchanger temperatures for many hydrocarbon feed streams. A flow rate of 6 pounds per hour was used while maintaining an operating pressure of 150 p.s.i.g. During our investigation of the fouling problems it was found that tube deposits were not significant and it was not practical to use tube appearance as a method of evaluation. Accordingly, the filter pressure drop was used as the most important factor in evaluating these tests.

During these tests the filter pressure drop was recorded at 10-minute intervals. It was found that the pressure drop varies exponentially with time and a plot of the log of the filter pressure drop against time gives a straight line. This relationship is expected since plugging of the filter increases velocity, and pressure drop varies with the square of the velocity. Thus, high temperature degradation product accumulation (fouling tendency) may be compared by a comparison of the slope of the resulting straight lines. The slope of the straight line is, of course, calculated as $(\log \Delta P_2 - \log \Delta P_1) / (T_2 - T_1)$ where ΔP and T represent filter pressure drop and time respectively for two different time ΔP measurements during the run.

Comparison of the slope of the various lines can be made easier by assigning an arbitrary "fouling index" of 1 to the slope of one line and comparing all other slopes to it. To best illustrate the anti-fouling effect of the additives tested, the slope of the hydrocarbon having had no previous air contact is chosen as a base with fouling index of 1. Thus, a line with fouling index of 2 means the slope of the straight line plotted as hereinbefore described is twice as great as for the hydrocarbon with no air contact, or in other words, the "fouling index" is twice as great.

Example 21

Various oils were subjected to the above coker test with and without anti-foulant additive incorporated therein. The anti-foulant additive used during these comparative tests was prepared as described in Example 18 above. The anti-foulant additive concentrations given are the concentrations of a mixture of the alkenylsuccinimide derivative of polyamino urea and about an equal volume of oil as in Examples 18-20 above. The data obtained during these tests are shown in Table VI.

TABLE VI

Test	Test Oil	Fouling Index of Test Oil	Anti-fouling Conc., p.p.m.	Fouling Index with Anti-foulant
A	Desulfurizer feed naphtha	0.2	10	0
B	Blend: 10% Gas oil, 90% kerosene	5.5	40	0.8
C	Blend: 10% crude oil (desalted), 90% kerosene	4.3	20	2.3
D	Naphtha	3.9	2.5	1.7
E	Kerosene "a"	2.1	2.5	0.6
F	Distillate	3.5	5.0	0.4
G	Kerosene "b"	2.9	10	0.4
H	Reformer desulfurizer feed naphtha	3.0	2.5	0.3

secutively through an in-line filter, a rotameter and a preheater. In the preheater the test hydrocarbon flows through an annulus enclosing a polished aluminum or carbon steel tube. An electrical heating element inside the tube heats the liquid hydrocarbon to a controlled predetermined temperature. Hot liquid hydrocarbon from the preheater annulus can be further heated to a higher temperature before the hydrocarbon is passed through a precision sintered stainless steel filter. The hot liquid hydrocarbon from the sintered filter is cooled by a water-cooled heat exchanger and then flows to a container on a scale for flow rate control. An operating pressure of about 150 p.s.i.g. is normally used but the pressure regulator can be set at other pressures.

Example 22

This example shows that polyalkylene polyamines other than tetraethylene pentamine may be used in preparing the anti-foulant.

An anti-foulant additive was produced as in Example 18 except that half of the tetraethylene pentamine (TEPA) was replaced with an equivalent number of moles of pentaethylene hexamine (PEHA). A heavy virgin naphtha was subjected to the above coker test. Without additive the naphtha had a fouling index of 5.0. With 2 p.p.m. of the anti-foulant used in Example 21 the naphtha had a fouling index of 1.1, and also with 2 p.p.m. of the 75 anti-foulant additive described above in this example

made from half TEPA and half PEHA the fouling index was 1.1.

Although the present invention has been described with reference to specific examples and specific preferred embodiments thereof, the invention is not to be considered as limited thereto but includes within its scope such modifications and variations as come within the spirit of the claims.

Having disclosed the invention and exemplified it with respect to the use of typical anti-foulant additive in typical hydrocarbon feed streams, what is claimed is:

1. A method of inhibiting the deposition of fouling materials on the surfaces of equipment by liquid hydrocarbon having a propensity for depositing such materials while being passed through such equipment at temperatures of from 300 to 1500° F., which method comprises incorporating in said liquid hydrocarbon a small amount of an alkenylsuccinimid derivative of polyamino urea.

2. The method of claim 1 wherein said amount is in the range of about 1 to 100 p.p.m. by weight based on said hydrocarbon.

3. The method of claim 1 wherein said liquid hydrocarbon is a petroleum hydrocarbon fraction from catalytic cracking to be subjected to hydrocarbon conversion for gasoline blending stock.

4. The method of claim 1 wherein said liquid hydrocarbon is a partially refined distillate fuel feed for hydrodesulfurization.

5. The method of claim 1 wherein said liquid hydrocarbon is a naphtha feed for catalytic reforming.

6. The method of claim 1 wherein said liquid hydrocarbon is a gas oil feed for catalytic cracking.

7. The method of claim 1 wherein said liquid hydrocarbon is desalted crude petroleum.

8. The method of claim 1 wherein said liquid hydrocarbon is produced during coking of a heavy petroleum fraction.

9. The method of claim 1 wherein said alkenylsuccinimid derivative is formed by reacting a polyalkylene amine, said amine having the general formula

10 wherein x is an integer of from 2 to 10, R is selected from the group consisting of hydrogen and lower alkyl hydrocarbon substituents having up to about 8 carbon atoms and alkylene is a divalent open chain hydrocarbon group having from 1 to 8 carbon atoms, with urea in a ratio of about two moles of said amine per mole of urea to form polyamino urea and then reacting said polyamino urea with mono-alkenyl substituted succinic anhydride having as the alkenyl substituent a hydrocarbon group derived from polyolefin having at least 30 carbon atoms per molecule.

10. The method of claim 9 wherein said polyalkylene amine reaction with urea is carried out at a temperature in the range of about 200 to 500° F. and said reaction of said polyamino urea with mono-alkenyl substituted succinic anhydride is carried out at a temperature in the range of about 200 to 450° F.
